UNITED STATES PATENT OFFICE

JOHN B. AUFLUDISH, OF DAYTON, OHIO, ASSIGNOR TO THE MULTIPLE VALVE AND MANUFACTURING COMPANY, OF DAYTON, OHIO, A CORPORATION OF OHIO

MULTIPLE VALVE

Application filed February 23, 1927. Serial No. 171,476.

This invention relates to multiple valves and is designed more particularly for controlling the flow of fluid to an apparatus the operation of which requires that different fluids shall be passed through the same successively, such as bakelite molds, water softeners and the like. For example, in molding bakelite the material to be molded is first heated and subjected to pressure and then cooled. To effect these operations live steam is passed through the jacket surrounding the mold and forming a part thereof, the application of steam being continued for a length of time sufficient to properly heat and press the material. At the end of this operation the steam is cut off and water is passed through the jacket to cool the mold. The steam which is passed through the jacket is discharged to a trap or other receptacle from which it may be withdrawn for other purposes, such as heating the building, and the water is discharged to the drain. After the cooling operation and before a subsequent heating operation the water must be removed from the mold. This is usually accomplished by admitting steam to the jacket and blowing the water out of the jacket to the drain. These several operations are effected by the manipulation of a plurality of individual valves. For the heating operation the steam inlet valve and the discharge valve leading to the trap must be opened and then closed. For the cooling operation the water inlet valve and the drain discharge valve must be opened. When the cooling operation has been completed the water valve is closed and the steam valve opened to permit the steam to pass through the jacket to discharge the water to the drain. If the blowing out operation is effected immediately following the cooling operation the steam inlet valve and the drain valve must be then closed. However, it is customary to effect the blowing out operation after the mold has been refilled and is ready for another heating operation and when this is done the water inlet valve will be closed at the end of the cooling operation and when the blowing out of the water is to be effected the steam valve is opened, the drain valve being already open, and after the blowing out

of the water the drain valve is closed and the trap valve opened, thus again effecting the heating operation. Not only is the manipulation of these individual valves a slow process but the sequence of operation depends entirely upon the operator and it is very easy to open or close the wrong valves or valve and even if this had no other undesirable result it would produce additional delay and loss of time.

One object of the invention is to embody the several controlling valves in a unitary structure with a valve actuating mechanism for opening and closing the valves in their proper sequence, an inlet valve and an outlet valve being opened or closed upon each operation of the mechanism.

A further object of the invention is to provide such an apparatus in which the several operations will be so controlled as to insure the proper sequence.

A further object of the invention is to provide such a valve mechanism which will be simple in its construction, easily and quickly operated and which will not be liable to get out of order.

Other objects of the invention will appear as the mechanism is described in detail.

In the accompanying drawings Fig. 1 is a side elevation of a multiple valve embodying my invention; Fig. 2 is a plan view of the same, partly broken away; Fig. 3 is a vertical sectional view taken on the line 3-3 of Fig. 2; Fig. 4 is a transverse sectional view taken on the line 4-4 of Figs. 1 and 3; Fig. 5 is a transverse sectional view taken on the line 5-5 of Figs. 1 and 3; Fig. 6 is a detail sectional view taken on the line 6-6 of Fig. 2; Fig. 7 is a detail view of the supplemental valve actuating device; Fig. 8 is a detail view of the valve actuating device showing one of the cam surfaces; Fig. 9 is a plan view of the valve as a whole, partly broken away, showing a slight modification thereof; Fig. 10 is a section taken on the line 10-10 of Fig. 9; and Fig. 11 is a section taken on the line 11-11 of Fig. 9.

In these drawings I have illustrated one embodiment of my invention and have shown a form of device adapted for application

either to a bakelite mold or to a water softening apparatus. It will be understood, however, that this particular embodiment has been chosen for the purpose of illustration only and that the multiple valve may be used for various purposes, the number of individual valves may be varied and the character and arrangement of the various parts of the mechanism may be modified to secure the desired operations in the desired sequence, all without departing from the spirit of the invention.

The multiple valve here illustrated comprises a main housing having a plurality of passageways therethrough with individual valves for controlling these passageways and is provided with a valve actuating mechanism which will operate the valves in the desired sequence and which, in the present instance, causes the opening or closing of one inlet valve and one outlet valve simultaneously. Preferably the passageways are in the form of chambers, the corresponding chambers having valve controlled communication. In describing the valve here illustrated I will assume that it is connected with a bakelite mold and will describe the operations necessary with such an apparatus and will refer to the fluids there employed. In this particular embodiment of the invention the housing which is shown at 1, is substantially cylindrical in form and comprises upper and lower portions, each portion being provided with a plurality of chambers and the chambers in the two portions being connected by valve controlled ports. The lower portion of the housing, as shown in Fig. 5, has an individual steam inlet chamber 2 provided with means, such as an inlet port 3, for connecting the same with a suitable source of steam supply. It also has an individual water inlet chamber 4 provided with means, such as a port 5, for connecting the same with a source of supply of water. Also arranged in this lower portion of the housing is a main discharge chamber 6 having means, such as a port 7, for connecting the same with the apparatus through which the fluids are to be passed which, in the present instance, is the mold. The upper portion of the housing, as shown in Fig. 4, has a main inlet chamber 8 arranged directly above and of a size substantially equal to the two individual inlet chambers 2 and 4. This main inlet chamber has means, such as a port 9, for connecting the same with the apparatus or mold to which the fluids are to be delivered. Each individual inlet chamber is connected with the main inlet chamber by a port 10 and this port is controlled by a suitable valve. In the present arrangement I have employed a reciprocating valve and have shown the same as comprising a disk-like member 11 adapted to engage a seat at the lower end of the port 10. This disk-like valve member is carried

by a valve stem 12 which extends through the port 10 and has its lower portion slidably mounted in a guideway 13 in the bottom of the housing and has its upper end slidably mounted in a stuffing box 14 in the top wall 70 of the housing, the upper end of the stem extending above the end of the stuffing box. A spring 15 confined between the disk 11 and the bottom of the housing tends to hold the valve normally on its seat and thus interrupt the communication between the individual inlet chamber and the main inlet chamber. It will be apparent that by opening the valve of the steam inlet chamber 2 steam will be allowed to pass through that chamber into the main inlet chamber and through the port 9 to the mold. When this valve is closed and the valve in the water inlet chamber 4 is opened water will pass through the chamber 4 into the main inlet chamber and through 80 the port 9 to the mold. Thus the passageways for steam and for water are in part separate and in part the same. The upper portion of the housing also has an individual steam discharge chamber 16 provided with 90 means, such as a port 17, for connecting the same with a trap, and an individual water discharge chamber 18 having means, such as a port 19, for connecting the same with a drain. These individual discharge chambers 95 are connected with the main discharge chamber 6 by ports 20 which are controlled by outlet valves 21 of a construction and arrangement similar to the valves 11. When the outlet valve of the steam discharge chamber 16 is opened steam will pass from the mold to the main discharge chamber 6, through the port 20 to the individual discharge chamber 16 and through port 17 to the trap. When the valve of the individual 100 water discharge chamber 18 is open the water will pass from the mold through the main discharge chamber to the individual discharge chamber and thence to the drain. Consequently when the steam inlet valve 11 105 is open and the steam outlet valve 21 is open the steam will pass from the source of supply through the inlet chambers of the valve housing to the mold, from the mold to the discharge chambers of the housing and thence 110 to the trap. When the steam inlet and discharge valves have been closed and the water inlet and discharge valves opened the water will pass from the source of supply through the housing to the mold and back to the housing and thence to the drain. When the valve 11 of the steam inlet chamber 2 is opened and the outlet valve of the discharge chamber 18 is opened the steam will pass from the source of supply through the housing 115 and the mold and out through the water discharge chamber to the drain, thus forcing all the water out of the mold to the drain. 120

It is desirable that the valves should be readily accessible and removable and for this 130

purpose the bottom wall of the housing 1 is provided with openings in line with the respective ports 10 and 20 and of a size sufficient to permit the valves to be moved through the same. These openings are closed by screw threaded plugs or caps 22 which can be readily removed and the guideways 13 for the valve stems are formed in these plugs. Thus by removing any one of these plugs the valve can be removed and reinserted without disturbing any of the other valves or any other part of the mechanism.

Suitable mechanism is provided for controlling the several valves and this mechanism is preferably of such a character that the valves will be operated in pairs, the two valves of each pair being opened or closed simultaneously, or substantially simultaneously. As has been stated, the valve stems extend above the stuffing boxes in which they are mounted and, in the present construction, I have mounted on the top wall of the housing 1 an actuating device 23 which is disk-shaped in form and is journaled on a stud 24 mounted in the top of the housing. This disk-shaped member or plate 23 is provided with two depending cam portions 25 which are so arranged that they will normally lie between the stems of the two inlet valves and the stems of the two outlet valves so that the movement of the actuating device in one direction will cause the cams to engage the steam inlet valve and the outlet valve leading to the trap and the movement of the actuating device from its normal position in the other direction will cause the cams to engage and open the water inlet valve and the outlet valve leading to the drain. When the actuating device is in its normal position all the valves will be closed. The actuating device is provided with a handle 26 by means of which it may be manipulated and is also provided with lugs 27 arranged to engage a fixed stop, such as a pin 28, and thus limit the movement of the actuating device in either direction.

In order to connect the steam inlet chamber 2 with the discharge chamber leading to the drain a supplemental actuating device has been provided. As shown more clearly in Figs. 6 and 7 this supplemental actuating device comprises a vertically movable actuating member or plate 29 of a length slightly greater than the distance between the steam inlet valve and the drain valve and so arranged that when the main actuating device is in its normal position this supplemental plate will be arranged directly above the stems of said steam inlet valve and said drain valve. As here shown, the supplemental actuating member or plate is mounted for edge-wise movement in an opening 30 formed in the disk-like portion of the main actuating device, its upward movement being limited by projections or flanges 31 arranged beneath the main actuating device. Normally this

supplemental actuating device will rest lightly upon the upper ends of the two valve stems and when these valves are to be operated it is forced downwardly. Preferably this is accomplished by means of a cam 32 pivotally mounted at 33 on a bracket or lug 34 carried by and preferably formed integral with the main actuating device. This cam is provided with an actuating handle 35 and is so shaped that when the handle is moved to its upright position the valve actuating member 29 will be forced downwardly and the valves opened and because of the flat contour of the end of the cam the valve actuating member will be held in its depressed position until the cam is positively actuated to release the same and permit the valves to be moved upwardly by their springs. To prevent the steam inlet from being connected with the drain at the wrong time or to prevent the main valve actuating device from being operated while the valve actuating member 29 is in its depressed position I have provided a retaining device which is here shown as a lug 36 depending from the valve actuating member or plate 29 and so arranged that when the main valve actuating device is in its normal position this lug will lie above the upper ends of the adjacent stuffing boxes but in line with the space between the same so that the valve actuating member may be depressed. When the valve actuating member is in its depressed position the lug will lie between the stuffing boxes and will hold the main valve actuating device against movement in either direction. When the supplemental valve actuating device is in its elevated position and the main valve actuating device has been moved in either direction from its normal position the lug will overhang one or the other of the stuffing boxes and will prevent the supplemental actuating device from being depressed.

Water is supplied to this device under relatively high pressures and difficulty is sometimes experienced in controlling this pressure. In Figs. 9, 10 and 11, I have shown a modified arrangement of the mechanism adapted to more effectually control the high water pressures. The device shown in these figures is identical with that above described with the exception that means are provided for interposing an additional valve in the water line in series with the water inlet valve so that the water must pass both of these valves before it can leak into the main inlet chamber. As here shown, the housing is provided with a lateral extension 37, the lower portion of which is provided with a chamber 38 having means, such as a port 39, for connecting it with the source of water supply. Arranged directly above the chamber 38 is a second chamber 40 having open communication with the individual water inlet chamber 4. The chambers 38 and 40 are connected by a port 41 which is controlled by a valve 42

of the type above described and the stem 43 of this valve extends upwardly above the extension 37 of the housing and is arranged substantially in a radial line with the upper end 5 of the water inlet valve, so that when the main actuating device has been moved to a position to open the water inlet valve the handle 26 will extend outwardly across the stem of the valve 42, and I have provided the handle 10 26 with a depending portion or cam surface 44 so arranged that it will engage the valve stem 43 and open the valve 42, either at the same time that the water inlet valve is opened or immediately thereafter, so that both valves 15 will be opened and closed at substantially the same time. With this arrangement the main water pressure is exerted against the valve 42 and should there be any leakage about this valve the water will accumulate 20 in the individual water inlet chamber but the pressure thereon will be so slight that there will not be any leakage about the main water inlet valve.

As has been stated, this valve is adapted as 25 here shown for use with water softening apparatus of that type which employs an exchange base mineral as the softening agent. When so used the hard water supply pipe will be connected with the individual steam inlet 30 chamber and the regenerating solution or brine pipe will be connected with the individual water inlet chamber, while the main inlet chamber will be connected with the softener. The outlet pipe for the softener 35 will be connected with the main discharge chamber of the valve and the individual discharge chamber, here shown as leading to the trap, will be connected with the service line and the individual discharge chamber, here 40 shown as leading to the drain, will be connected with the drain. Thus upon the opening of what are here characterized as the individual steam inlet valve and the trap valve, the hard water would flow through the softener to the service line and upon the opening 45 of what are here characterized as the individual water inlet valve and the drain valve, the salt solution would flow from the softener to the drain. Upon the completion of the 50 reconditioning operation the steam inlet valve and the drain valve would be opened to permit hard water to flow through the softener to the drain and to wash out the salt solution, after which the drain valve would be 55 closed and the trap valve opened to restore the softening operation.

While I have shown and described one embodiment of my invention I wish it to be understood that I do not desire to be limited 60 to the details thereof as various modifications may occur to a person skilled in the art.

Having now fully described my invention, what I claim as new and desire to secure by Letters Patent, is:

65 1. In a multiple valve, a housing provided

with individual inlet chambers having means for connecting the same with separate sources of fluid supply, a main inlet chamber adapted to communicate with either of said individual inlet chambers and having means for connecting the same with an apparatus to which said fluids are to be successively delivered, valves to control the communication between said individual chambers and said main inlet chamber, said housing being also provided with a main discharge chamber having means for connecting the same with said apparatus, and individual discharge chambers adapted to communicate with said main discharge chamber and having means for connecting the same with separate points of discharge, valves to control the communication between said individual discharge chambers and said main discharge chamber, each of the aforesaid valves having a stem projecting beyond said housing, and an operable device mounted exteriorly of said housing and having parts to selectively engage said valve stems and actuate said valves to first connect one individual inlet chamber with said main inlet chamber and one individual discharge chamber with said main discharge chamber and to then interrupt said connections and connect another individual inlet chamber with said main inlet chamber and another individual discharge chamber with said main discharge chamber.

2. In a multiple valve, a housing provided with individual inlet chambers having means for connecting the same with separate sources of fluid supply, a main inlet chamber adapted to communicate with either of said individual inlet chambers and having means for connecting the same with an apparatus to which said fluids are to be successively delivered, valves to control the communication between said individual chambers and said main inlet chamber, said housing being also provided with a main discharge chamber having means for connecting the same with said apparatus, and individual discharge chambers adapted to communicate with said main discharge chamber and having means for connecting the same with separate points of discharge, valves to control the communication between said individual discharge chambers and said main discharge chamber, a device for actuating said

100 valves to first connect one individual inlet chamber with said main inlet chamber and one individual discharge chamber with said main discharge chamber and to then interrupt said connections and connect another individual inlet chamber with said main inlet chamber and another individual discharge chamber with said main discharge chamber, a device for actuating said

105 valves to first connect one individual inlet chamber with said main inlet chamber and one individual discharge chamber with said main discharge chamber and to then interrupt said connections and connect another individual inlet chamber with said main inlet chamber and another individual discharge chamber with said main discharge chamber, a device for actuating said

110 valves to first connect one individual inlet chamber with said main inlet chamber and one individual discharge chamber with said main discharge chamber and to then interrupt said connections and connect another individual inlet chamber with said main inlet chamber and another individual discharge chamber with said main discharge chamber, and other means for connecting the first mentioned individual inlet chamber with said main inlet chamber and the last mentioned individual discharge chamber with said main discharge chamber.

3. In a multiple valve, a housing comprising upper and lower portions, the lower portion of said housing having individual inlet chambers adapted to communicate with separate sources for fluid supply, and a main discharge chamber adapted to communicate with an apparatus through which fluid is to be passed, and the upper portion of said housing having a main inlet chamber adapted to communicate with said apparatus and having individual discharge chambers adapted to communicate with separate points of discharge, ports connecting said individual inlet chambers with said main inlet chamber, other ports connecting said individual discharge chambers with said main discharge chamber, separate valves to control the several ports, and means for actuating said valves. 70
- 10 4. In a multiple valve, a housing comprising upper and lower portions, the lower portion of said housing having individual inlet chambers adapted to communicate with separate sources of fluid supply and a main discharge chamber adapted to communicate with an apparatus through which fluid is to be passed, and the upper portion of said housing having a main inlet chamber adapted to communicate with said apparatus and having individual discharge chambers adapted to communicate with separate points of discharge, ports connecting said individual inlet chambers with said main inlet chamber, other ports connecting said individual discharge chambers with said main discharge chamber, 75 separate valves to control the several ports, and a valve actuating device having means for operating said valves in pairs to cause different fluids to be passed successively through said apparatus and discharged therefrom at different points. 80
- 15 5. In a multiple valve, a housing comprising upper and lower portions, the lower portion of said housing having individual inlet chambers adapted to communicate with separate sources of fluid supply and a main discharge chamber adapted to communicate with an apparatus through which fluid is to be passed, and the upper portion of said housing having a main inlet chamber adapted to communicate with said apparatus and having individual discharge chambers adapted to communicate with separate points of discharge, ports connecting said individual inlet chambers with said main inlet chamber, other ports connecting said individual discharge chambers with said main discharge chamber, 85 separate valves to control the several ports, and a valve actuating device having means for first opening the valve of one individual inlet chamber and the valve of one individual discharge chamber, then closing said valves and opening the valve of the other individual inlet chamber and the valve of the other individual discharge chamber, and then closing said valves and opening the valve of the last mentioned 90
- 20 individual inlet chamber and the valve of the first mentioned individual discharge chamber. 95
- 25 6. In a multiple valve, a housing having passageways to connect separate sources of fluid supply with an apparatus through which fluid is to be passed, inlet valves to control the respective passageways, said housing also having passageways to connect said apparatus with separate points of discharge, 100 outlet valves to control the respective last mentioned passageways, and a valve actuating mechanism having means to first open one inlet valve and one outlet valve, to then close said valves and open the other inlet valve and the other outlet valve, to then close the last mentioned inlet valve and to open the first mentioned inlet valve while the last mentioned outlet valve is open. 105
- 30 7. In a multiple valve, a housing having passageways to connect an apparatus with a source of steam supply and with a source of water supply, inlet valves to control the respective passageways, said housing also having passageways to connect said apparatus with a trap and with a drain, outlet valves to control the last mentioned passageways, a valve actuating mechanism having means to first open the steam inlet valve and the trap valve, to then close said valves and open said water inlet valve and said drain valve, and to then close the last mentioned valves and open said steam inlet valve and said drain valve. 110
- 35 8. In a multiple valve, a housing having a plurality of passageways, two pairs of valves to control the flow of fluid through said passageways, an actuating device for alternately opening and closing said pairs of valves, and means for opening one valve of each pair independently of the other valves. 115
- 40 9. In a multiple valve, a housing having a plurality of passageways, a plurality of separately operable inlet valves and a plurality of separately operable outlet valves for controlling the flow of fluid through said passageways, valve actuating mechanism having means for first opening and closing one inlet valve and one outlet valve, then opening and closing another inlet valve and another outlet valve, and for then opening and closing the first mentioned inlet valve and the last mentioned outlet valve. 120
- 45 10. In a multiple valve, a housing having a plurality of passageways, two pairs of valves for controlling the flow of fluid through said passageways, an actuating device having means for first opening and closing one pair of valves and then opening and closing the other pair of valves, and separately operable means or simultaneously opening one valve of each pair of valves independently of the other valves. 125
- 50 11. In a multiple valve, a housing having a plurality of passageways, two pairs of valves for controlling the flow of fluid. 130

through said passageways, an actuating device having cams arranged to open the valves of one pair when said device is moved in one direction from its neutral position and to then open the valves of the other pair when said device is moved in the other direction from its neutral position, and a device carried by said actuating device and movable relatively thereto to simultaneously open one valve of each pair.

12. In a multiple valve, a housing having a plurality of passageways, two pairs of valves for controlling the flow of fluid through said passageways, an actuating device having cams arranged to open the valves of one pair when said device is moved in one direction from its neutral position and to then open the valves of the other pair when said device is moved in the other direction from its neutral position, a device carried by said actuating device and movable relatively thereto to simultaneously open one valve of each pair, and means to prevent the operative movement of the last mentioned device when said valve actuating device has been moved from its neutral position.

13. In a multiple valve, a housing having a plurality of passageways, two pairs of valves for controlling the flow of fluid through said passageways, an actuating device having cams arranged to open the valves of one pair when said device is moved in one direction from its neutral position and to then open the valves of the other pair when said device is moved in the other direction from its neutral position, a device carried by said actuating device and movable relatively thereto to simultaneously open one valve of each pair, and means to prevent said valve actuating device from being moved from its neutral position when the last mentioned device is in its operative position.

14. In a multiple valve, a housing having a plurality of passageways, two pairs of valves for controlling the flow of fluid through said passageways, each of said valves having a stem extending above said housing, a main valve actuating device rotatably mounted on said housing and having cam surfaces arranged to open the valves of one pair when said device is moved in one direction and to open the valves of the other pair when said actuating device is moved in the other direction, and a supplemental valve actuating device movably mounted on said main valve actuating device and arranged to operatively engage one valve of each pair when said main valve actuating device is in its neutral position.

15. In a multiple valve, a housing having a plurality of passageways, two pairs of valves for controlling the flow of fluid through said passageways, each of said valves comprising a reciprocatory stem extending beyond the top of said housing, a stuffing

box for each valve stem, a main valve actuating device rotatably mounted on said housing and having cams arranged to engage the stems of one pair of valves when said valve actuating device is moved in one direction from its neutral position and to engage the stems of the other pair of valves when said actuating device is moved in the other direction from its neutral position, a supplemental valve actuating member movably mounted on said main valve actuating member and so arranged that it will overlie the stem of one valve of each pair of valves when said main actuating device is in its neutral position, and means for depressing said supplemental valve actuating member.

16. In a multiple valve, a housing having a plurality of passageways, two pairs of valves for controlling the flow of fluid through said passageways, each of said valves comprising a reciprocatory stem extending beyond the top of said housing, a stuffing box for each valve stem, a main valve actuating device rotatably mounted on said housing and having cams arranged to engage the stems of one pair of valves when said valve actuating device is moved in one direction from its neutral position and to engage the stems of the other pair of valves when said actuating device is moved in the other direction from its neutral position, a supplemental valve actuating member movably mounted on said main valve actuating member and so arranged that it will overlie the stem of one valve of each pair of valves when said main actuating device is in its neutral position, means for depressing said supplemental valve actuating member, and a part carried by said supplemental valve actuating member and adapted to extend between two of said stuffing boxes when said member has been depressed, to prevent the operation of said main valve actuating device.

17. In a multiple valve, a housing having a plurality of passageways, two pairs of valves for controlling the flow of fluid through said passageways, each of said valves comprising a reciprocatory stem extending beyond the top of said housing, a stuffing box for each valve stem, a main valve actuating device rotatably mounted on said housing and having cams arranged to engage the stems of one pair of valves when said valve actuating device is moved in one direction from its neutral position and to engage the stems of the other pair of valves when said actuating device is moved in the other direction from its neutral position, a supplemental valve actuating member movably mounted on said main valve actuating member and so arranged that it will overlie the stem of one valve of each pair of valves when said main actuating device is in its neutral position, means for depressing said supplemental valve actuating member.

mental valve actuating member, and a part carried by said supplemental valve actuating member and arranged to overlie one of said stuffing boxes when said main valve actuating device has been moved from its neutral position, and thus prevent the operation of said supplemental valve actuating member.

18. In a multiple valve, a housing having a plurality of passageways, two pairs of valves for controlling the flow of fluid through said passageways, each of said valves comprising a reciprocatory stem extending beyond the top of said housing, a stuffing box for each valve stem, a main valve actuating device rotatably mounted on said housing and having cams arranged to engage the stems of one pair of valves when said valve actuating device is moved in one direction from its neutral position and to engage the stems of the other pair of valves when said actuating device is moved in the other direction from its neutral position, a supplemental valve actuating member movably mounted on said main valve actuating member and so arranged that it will overlie the stem of the valve of each pair of valves when said main actuating device is in its neutral position, and a cam pivotally mounted on said main valve actuating device and arranged to engage said supplemental valve actuating member and depress the same.

19. In a multiple valve, a housing having a passageway to connect separate sources of fluid supply with an apparatus through which fluid is to be passed, inlet valves to control the respective passageways, said housing also having passageways to connect said apparatus with separate points of discharge, outlet valves to control the last mentioned passageways, a second valve arranged in one of the first mentioned passageways in series with the inlet valve of that passageway, and a valve actuating device for opening and closing said valves in predetermined order.

20. In a multiple valve, a housing having inlet passageways to connect separate sources of fluid supply with an apparatus through which said fluid is to be passed, an inlet valve to control the respective passageways, said housing also having outlet passageways to connect said apparatus with separate points of discharge, outlet valves to control the last mentioned passageways, a valve actuating device having two movements and arranged to open upon each movement thereof, one inlet valve and one outlet valve, a second valve interposed in one of said inlet passageways in series with the inlet valve of that passageway, said valve actuating device having means for opening the last mentioned valve when said other valve of said inlet passageways is opened.

21. In a multiple valve, a housing comprising upper and lower portions, the lower portion of said housing having individual in-

let chambers adapted to communicate with separate sources of fluid supply, and a main discharge chamber adapted to communicate with an apparatus through which fluid is to be passed and the upper portion of said housing having a main inlet chamber adapted to communicate with said apparatus and having individual discharge chambers adapted to communicate with separate points of discharge, ports connecting said individual inlet chambers with said main inlet chamber, other ports connecting said individual discharge chambers with said main discharge chamber, separate valves to control the several ports, said housing also having a supplemental inlet chamber interposed between one of said individual inlet chambers and the source of fluid therefor, a supplemental valve to control the flow of fluid through said supplemental chamber, and a valve actuating device having means for actuating said supplemental valve when the valve of the inlet chamber, with which said supplemental chamber is connected, is open.

In testimony whereof, I affix my signature hereto.
